UNITED STATES PATENT OFFICE.

WILLIAM D. SMITH, OF DENVER, COLORADO.

DESIGN FOR A MEDALLION, &c.

SPECIFICATION forming part of Design No. 18,034, dated January 31, 1888.

Application filed September 19, 1887. Serial No. 250,152. Term of patent 3½ years.

To all whom it may concern:

Be it known that I, WILLIAM D. SMITH, a citizen of the United States, residing at Denver, in the county of Arapahoe and State of Colorado, have invented and produced a new and original Design for a Medallion for the Ornamentation of Watch-Cases, Lockets, Medals, Charms, and Similar Articles of Jewelry, of which the following is a specification, reference being had to the accompanying drawings, forming part hereof.

The figure is a front plan view of my newly-designed medallion.

The leading feature of my design is a fanciful aggregation of conventional representations of mountain scenery, bringing together in contiguity in the one design many such, though ordinarily separated, features, the whole being surrounded by a raised circular 20 rim, as fully shown in the drawing, and hereinafter described.

In the drawing, the letter A indicates the medallion circular in general contour. Near the upper central portion is a prominent peak, B, at the head of a gulch or valley, E. Upon the face of this leading or prominent peak is a conventional representation of a cross formed

by intersecting indentations or depressions, representing clefts or gullies in the side of the mountain. Upon either side of the peak B 30 are other peaks, D D. In the foreground a gulch or valley, E, leads down, as stated, from the peak B, there being representations of trees upon its sides. In the immediate foreground, at the base of the gulch or valley E, 35 are depicted rocks F and a waterfall or cascade, G, while H is a raised circular rim surrounding all these features.

I claim—

The design for a medallion herein shown and described, consisting of the representation of a main peak having a cross upon its side or face, lower peaks on either side of such main peak, a gulch or valley leading to the foreground from such main peak, a waterfall or 45 cascade, and the accompanying features of mountain scenery shown, the whole being surrounded by a raised circular rim, H.

In testimony whereof I affix my signature in presence of two witnesses.

WILLIAM D. SMITH.
